UNITED STATES PATENT OFFICE.

HEBER ROBARTS, OF BELLEVILLE, ILLINOIS.

WINDOW-LOCK.

1,360,800.

Specification of Letters Patent. Patented Nov. 30, 1920.

Application filed June 26, 1920. Serial No. 391,939.

To all whom it may concern:

Be it known that I, HEBER ROBARTS, a citizen of the United States, residing at Belleville, in the county of St. Clair and 5 State of Illinois, have invented a new and useful Window-Lock, of which the following is a specification.

This invention aims to provide a simple means for locking the upper and lower 10 sashes of a window, so that the joint between the meeting rails of the sashes will be dust proof, the sashes being so held that they will not rattle and it being practically impossible to slide either of the sashes when 15 the fastener is applied thereto.

It is within the province of the disclosure to improve generally and to enhance the utility of devices of that type to which the invention appertains.

20 With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings:—

Figure 1 shows in front elevation, a portion of a window frame and a pair of sashes, the fastener being applied thereto and being in a retracted position; Fig. 2 is an elevation wherein the fastener is viewed endwise; Fig. 3 is a plan of the fastener; and Fig. 4 is a fragmental section taken approximately on the line 4—4 of Fig. 1.

The numeral 1 denotes a portion of a 40 window frame carrying an outer guide strip 2, an inner guide strip 3 and a parting strip 4.

The numeral 5 denotes the stile of an upper sash and the numeral 6 denotes the stile of a lower sash—all as common and 45 well understood.

The fastener forming the subject matter of this application comprises a body 7 provided at its ends with oppositely projecting flanges 8 and 9 having transverse slots 10, the slots being open at one end, one flange being prolonged to form a finger 11 having an outstanding rib 12 beveled at one end, as shown at 14. The corners of the flanges 8 and 9 may be bent to form finger pieces 15. 55 As indicated by the numeral 16, the body 7 is curved longitudinally, or convexed, to a slight extent.

Securing devices 17, such as screws, are inserted into the stile 5 of the upper sash and into the stile 6 of the lower sash. The 60 body 7 of the fastener rests on the upper end of the stile 6 of the lower sash, the flange 8 co-operates with the vertical surface of the stile 5 of the upper sash, and the flange 9 co-operates with the vertical surface of the 65 stile 6 of the lower sash, the securing devices 17 being received in the slots 10. It will be seen from the foregoing, that the sashes are connected in such a way that one sash cannot be opened independently of the other, 70 the sashes being held together, transversely, so as to effect a dust proof joint between their cross rails. The body 7 is curved as shown at 16, and, then the fastener is slid to the right (Fig. 1) until the securing devices 75 17 are received in the slots 10, the body 7 is flattened to a slight extent. The fastener, therefore, is engaged with the securing devices 17 and bears on the upper end of the stile 6 with a spring pressure. By 80 means of the finger piece 15, the fastener may be slid to the right (Fig. 1) until the rib 12 enters between the stile 5 of the upper sash and the parting strip 4, as indicated in Fig. 4, the sashes thus being held against 85 rattling.

Having thus described the invention, what is claimed is:—

1. A sash fastener comprising a body having oppositely projecting flanges at its ends, 90 the flanges being provided with transverse slots which are open at one end.

2. A sash fastener comprising a resilient body which is curved longitudinally, the body being provided at its ends with oppositely projecting flanges, the flanges having 95 transverse slots, the slots being open at one end.

3. A sash fastener comprising a body having oppositely projecting flanges at its ends, 100 the flanges being provided with transverse slots which are open at one end, one flange being prolonged to form a finger having an outstanding rib.

In testimony that I claim the foregoing 105 as my own, I have hereto affixed my signature in the presence of two witnesses.

HEBER ROBARTS.
